(57) **CLAIM**

The ornamental design for a vehicle front end, as shown and described.

DESCRIPTION

FIG. 1 is a front perspective view of the vehicle, showing my new design, the dashed line portion being illustrated for locational reference and forming no part of my inventive design;

FIG. 2 is a front elevational view thereof;

FIG. 3 is a side elevational view thereof; and,

FIG. 4 is a top view thereof.
